UNITED STATES PATENT OFFICE

2,316,000

AUTOMATIC CRANKCASE OIL FILLER

Alfred O. James, Detroit, Mich.

Application May 31, 1940, Serial No. 338,037

1 Claim. (Cl. 184—103)

The present invention relates to a new and improved device for automatic gauging of a quantity of oil in the crank case and means for automatically supplying oil from a supply tank to the oil pump of an engine having an oil pump system or force feed when the oil becomes exhausted to a predetermined low level in the crank case.

It is known that the latest type of automobile engines and the like are equipped with an oil pump system, and are lubricated by means of an oil pump controlled by the cam shaft with oil tube lines connected inside the motor from the oil pump to parts such as main bearings, piston rods, caps, and other movable parts.

The oil in this type of motor is located beneath the crankshaft and the oil can not be splashed upon the crankshaft, piston rods, or parts by the piston rod caps. The only means by which the oil can be supplied to such parts in this type of engine is by means of the oil pump drawing oil from the crank case by means of a tube extended from the drawing side of the oil pump into the oil within the crank case. The operation of the oil pump gears creates an oil pressure in the oil tube lines and is known as, "oil pump system or force feed."

It is the primary object of this invention to provide an oil supply tank having direct communication with the engine's oil pump through the use of the control box or unit for allowing the oil pump to draw fresh oil immediately from the supply tank when the oil in the crank case becomes suddenly exhausted or consumed by the engine's use. It is to be carefully noticed that the oil pump will supply the revolving crankshaft, piston rods and caps before the crank case is refilled.

A further object of the invention is to keep an ample supply of oil in the reservoir and a control unit where an adjustment can be made to control the refilling point of the crank case and means for allowing the engine's oil pump to replenish the crank case while the motor is in motion, or while traveling on the highway.

A still further object of this invention is to provide a control box secured adjacent the crank case of an engine and having direct communication therewith. Positioned within the control box is a float with a sleeve slidable upon a shaft positioned within the control box and adapted to rise and fall with the level of the oil and means associated with the float for opening and closing a direct communication from the oil pump to the supply tank.

These and further objects will be more fully

illustrated in the accompanying drawings and described in the following specification and appended claim.

Figure 1 is a vertical sectional view illustrating the invention from the front end, it being understood that the supply tank may be positioned at any convenient part of the automobile.

Figure 2 is a top plan view partially in section taken on line 2—2 of Figure 1.

Figure 3 is a sectional view taken on line 3—3 of Figure 1.

Figure 4 is a vertical section illustrating the invention from the side.

Figure 5 is a top plan view partially in section taken on line 5—5 of Figure 4.

It is known that the greatest hazard of automobile owners occurs when the supply of oil has been exhausted, causing the burning out of the main and rod bearings, in fact seriously affecting all movable parts of the engine. This often occurs because the oil pressure gauge shows oil pressure on the said gauge until the oil is completely exhausted in the crank case.

At the present time there are various instruments for testing the level of oil in the crank case of the engine, such as a meter positioned on the dash board of an automobile having an indicator arm operated by the oil pressure from the oil pump.

Another means of testing the quantity of oil in the crank case is by the gauge rod positioned beneath the hood of the engine and usually in proximity to the breather tube. In order to test the level of oil it is necessary to remove the gauge rod, remove the oil therefrom and again insert it into the crank case and upon withdrawing the gauge rod the level of the oil can be determined.

By the use of the present invention it is not necessary to make use of any mechanical means for indicating the supply of oil in the crank case. As soon as the oil has reached the predetermined low level the supply will be automatically replenished from the supply tank.

Referring to the drawings, the numeral 6 illustrates a partial sectional view of the crank case of an automobile engine having an oil intake tube 7 positioned therein and connected with oil pump 8. The oil pump may be of any desired construction and is used for illustrating only, a partial view thereof being shown.

The inlet tube 7A is connected to the drawing side of the oil pump and the other end to a line for direct communication with the supply tank, to be later described.

Removably secured at one side 6A of the crank

case 6 is a control box 9 secured to the crank case through the medium of bolts or the like 10. The bottom portion 11 of control box 9 is removably secured with a gasket 11A through the use of screw threaded bolts 12 and has forming an integral part thereof guide 13 which is provided within portion 20 of bottom 11. Guide 13 is adapted to receive vertical shaft 14 for slideable movement the shaft being controlled by sleeve 15A within float 15.

When attaching control box 9 to the crank case 6 gasket 16 is positioned between the two members and the corresponding passages 17 cause direct communication between the crank case and the control box for maintaining an exact level of the lubricant in each of the members.

It is to be understood that float 15 has sufficient space within control box 9 to allow the oil to rise to the same level as in crank case 6. The float 15 is slideable upon shaft 14 and for limiting the movement thereof, there is provided a pair of pins 18 and 19, the pin 18 being positioned at the lowermost part of the shaft for limiting the downward movement of float 15. Pin 19 is positioned at the uppermost portion of the shaft for limiting the upward movement of the float.

Therefore when the level of oil in crank case 6 and control box 9 gradually diminishes the float 15 gradually moves downwardly until it touches pin 18 of shaft 14.

At this point it is desired to indicate that pins 18 and 19 may be adjusted to allow the float to move vertically a longer or shorter distance, depending upon the amount of oil used by the engine, also how often one desires to refill his engine's crank case. The control shaft is provided with a series of holes 42 for pins 18 and 19, said pins resetting holes 42 are located at the uppermost portion and at the lowermost portion of said shaft. Therefore setting pins 18 and 19 in holes closest to the center of said shaft 14 will thereby shorten the movement of float 15, causing the device to operate when a small quantity of oil has been consumed from the crank case. Whereby placing pins 18 and 19 farther apart on shaft 14 the quantity of oil in the crank case will become more nearly exhausted before the device will operate.

It is to be understood that when the float 15 engages pin 18 on its downward movement it will not proceed immediately downwardly with control shaft 14. It is to be noticed in Figure 4 a pressure is secured on shaft 14 by means of a ball and spring which are located in passage 51. The pressure is maintained on said shaft while the device is not supplying oil to the oil pump to prevent slipping or dropping while float 15 is moving from pin 19 to pin 18. Therefore the float becomes lodged upon pin 18 until the motor has consumed the oil from the topmost part of said float to the lowermost part thereon. This leaves the float above the oil surface and converts it into a deadweight upon shaft 14, to be later described.

It is necessary to indicate that an air vent hole 47 is provided in upper portion 23A preventing air from forming over oil within control box 9. Cap 48 is filled with a fine mesh wire which is pressed into the outer end of the vent hole to prevent said hole from becoming blocked with dirt.

The upper portion 23A of control box 9 is constructed with passage 21 which extends from the outer edge of the case to bore 23. Tube 22

is directly connected from the outer end of passage 21 to the intake manifold of an engine. A pocket chamber 27 is formed when the upper portion 23A and top portion 30 are assembled. A flexible diaphragm 24 is provided and is secured between the two said members by the use of the screwthreaded stud bolts or the like 29. The diaphragm is operated when the vacuum in the tube 22 reaches chamber 27. For controlling valve 25, said valve is directly connected with said diaphragm through the medium of a screwthreaded stud bolt 26. The spring retainer 23 over valve 25 of the upper portion 30 is a stop member for limiting the downward movement of valve 25.

A cover is provided for the upper portion 23A and is bolted or otherwise secured thereto through the use of screws 29. The cover is generally indicated by the numeral 30 and it is to be noted that bore 31 projects through the central portion thereof for guiding and supporting valve 25, said valve having an opening 32 adapted to align with the transverse openings 33 in cover 30 when said valve is operated. The upper portion of valve 25 has a spring 34 for returning said valve to its topmost position when the vacuum is broken. A dust cover 35 and gasket 35A are provided and are secured to cover 30 by any suitable means such as screws or the like 36.

Upper portion 23A has also a pressure control assembly for vacuum control shaft 14 and to be noted in Figure 4 a spring retainer 28 is secured to valve 25 by means of a screwthreaded stud bolt 28A. The spring retainer has an arm extending horizontally through cover 35 with allowable space for vertical motion therein. Connected to one end of 28 is a pressure control shaft 43 which is secured thereto by means of stop washer 54 and a screwthreaded nut 53. Bore 44 is provided and is adapted to receive said shaft 43 for vertical slideable movement therein, when valve 25 is drawn down by the vacuum in chamber 27. The pressure control shaft 43 has groove 46 and is constructed with an angle at the lowermost part of said groove. Groove 46 in shaft 43 is adapted to receive plunger 45 located in passage 51, the said plunger being constructed with one ball end for sliding on the inclined surface within groove 46 for releasing pressure of spring 49 and ball 50 on control shaft 14, while the device is in operation supplying oil to the oil pump. The said shaft 14 remains free from pressure by spring 49 until the crank case is refilled and the vacuum is broken in chamber 27, this action permitting spring 34 on valve 25 to force back in topmost position the valve 25 and pressure control shaft 43. At the same time the plunger is forced to the left due to its ball-end sliding over the lower inclined surface of groove 46 in shaft 43. It is to be noted a screwthreaded plug 52 is provided at the outer end of passage 51.

It is necessary to indicate that no false action occurs to diaphragm 24 by vacuum tube 22, while shaft 14 is in its topmost position, or while said shaft passes beyond passage 21. Spring 34 on valve 25 has the strength to require full suction of vacuum tube 22 through passage 21 to operate diaphragm 24.

Referring again to oil pipe line it is to be noted that the inlet tube 7A is coupled to the upper portion 37 of crank case 6A and to feed pipe 38 which in turn is coupled to cover 30. Feed pipe 38 and tube 7A of the oil intake are in direct communication with the transverse opening 33 of cover 30. There is also provided a tube 39

coupled to cover 30. Tube 39 is in direct communication with the supply tank 40, said supply tank being positioned at any convenient part of the automobile. A partial sectional view of the supply tank 40 is illustrated in Figure 1 and has cap 41 for replenishing the supply of oil within the tank. Tube 39 is coupled to the tank and projects therein as illustrated.

In the operation of the device when the oil within crank case 6 diminishes the oil in control box 9 will likewise diminish causing the float to lower gradually until it engages pin 18. At this point float 15 becomes lodged upon pin 18 and both float 15 and shaft 14 remain at a steadfast position until the motor has consumed a sufficient amount of oil so as to leave float 15 above the oil level in both crank case 6 and control box 9. The float at this point becomes additional weight upon pin 18 through the core 15A within float 15. After this action occurs said float and shaft have the controlling weight over the pressure spring 49 at passage 51 and the said shaft and float will move by the degrees downwardly within bore 23 and guide 13 as the oil diminishes until the upper end of control shaft 14 passes beyond the opening of the recess 21. A vacuum is then created through the vacuum tube 22 forcing diaphragm 24 and the valve 25 carried thereby downwardly until the spring retainer 28 over valve 25 abuts the top surface of upper portion 30.

At this point passage 32 is in direct communication with the transverse opening 33 and the oil pump will draw fresh oil from supply tank 40

through feed pipes 39 and 38 into oil intake tube 7A then to oil pump 8.

While the supply of oil in crank case 6 is being replenished the float rises likewise on shaft 14 and will abut pin 19 raising control shaft 14. Thus closing the vacuum in passage 21 and thereby returning diaphragm 24, valve 25 and shaft 43 to its topmost position through the aid of coil spring 34.

10 It is to be understood that this device will operate only while the motor is running since a vacuum is created by connections with the intake manifold to operate the movable parts.

Having thus fully described my invention, what

15 I claim as new is:

In an automatic crank case oil filler for supplying oil to an engine pump, the same comprising a control unit secured to said crank case, the top portion of said control unit removably secured to the bottom portion thereof for forming a chamber therein, a valve vertically positioned within a bore of said top portion, a pipe line directly connected to a supply tank and to an oil pump by the use of a transversely extending

20 passage positioned within the aforesaid top portion, a diaphragm positioned intermediate the control unit and the top portion thereof, the said valve being adjacent said diaphragm within said chamber, the control unit having a bore and a passage for a vacuum line to control said diaphragm and valve, and means to open and close the aforesaid transversely extending passage.

25 30 ALFRED O. JAMES.
